NECKLACE OR SIMILAR ARTICLE

Michael Chernow, New York, N. Y.

Application January 26, 1950, Serial No. 7,506

Term of patent 14 years

(Cl. D45—16)

To all whom it may concern:

Be it known that I, Michael Chernow, a citizen of the United States, and residing at New York, in the county of New York and State of New York, have invented a new, original, and ornamental design for a Necklace or Similar Article, of which the following is a specification, reference being had to the accompanying drawings, forming part thereof.

The figure shows a perspective view of the necklace or similar article, showing my new design.

I claim:

The ornamental design for a necklace or similar article, substantially as shown.

MICHAEL CHERNOW.
